SHINGLE AND ROOFING

Harry F. Wildman, Orlando, Fla.; Vincent Y. Wildman, executor of the estate of said Harry F. Wildman, deceased

Application December 30, 1935, Serial No. 56,819

13 Claims. (Cl. 108—7)

This invention relates to an improved shingle and to a completed roofing structure formed thereby, an object being to provide a construction of reinforced metal shingle which will present an efficient shingle structure and also an efficient roofing structure when properly assembled.

Another object of the invention is to provide an improved metal shingle which when in place on a roof gives the appearance of a conventional shingle while actually presenting strips of reinforced metal sheeting.

An additional object of the invention is to provide an improved roofing formed of reinforced metal shingles which are turned over and interlocked at each course with a retaining metal strip coating with the turned-over portion.

A further object is to provide an improved roofing structure which may be adjusted to any form of inclined roof and also to the eaves, valleys and crowns.

In the accompanying drawings:

Fig. 1 is a fragmentary perspective view of a roof with shingles and a roofing structure applied thereto and disclosing an embodiment of the invention;

Fig. 2 is a plan view of a short section of the shingle structure shown in Fig. 1, certain parts being broken away for better illustrating the construction;

Fig. 3 is a plan view of a reinforcing strip of material embodying certain features of the invention.

Fig. 4 is a fragmentary sectional view through Fig. 2 approximately on the line 4—4, the same being on an enlarged scale;

Fig. 5 is a view similar to Fig. 4 but showing the section taken on line 5—5 of Fig. 2;

Fig. 6 is an enlarged fragmentary sectional view through Fig. 2 on line 6—6;

Fig. 7 is a fragmentary perspective view showing two shingle strips connected together but before they are moved to a finished position;

Fig. 8 is a view similar to Fig. 7 but showing the edge of the strips bent over and clinched;

Fig. 9 is a perspective view of one of the retaining or clamping plates shown in Fig. 1;

Fig. 10 is an enlarged fragmentary sectional view showing part of a roof with the adjacent edges of shingles and a retaining plate associated therewith;

Fig. 11 is a perspective view of a retaining plate used in connection with the crown or apex of a roof;

Fig. 12 is a sectional view showing part of a

roof and how the shingles are applied to the apex thereof;

Fig. 13 is a sectional view illustrating how the shingles are applied adjacent the eaves of a roof;

Fig. 14 is a view similar to Fig. 13 but showing the shingles in a complete finished position;

Fig. 15 is a view similar to Fig. 12 but showing a valley with the shingles embodying the invention applied thereto, one part being completed and the other partially completed.

Referring to the accompanying drawings by numeral, 1 indicates a strip of shingles ready to be formed into the roofing 2 which is secured to the roof 3 by the various nails 4 extending through the retaining and clamping plates 5. When the shingle strip 1 is in place as shown in Fig. 1, the roofing structure presents the appearance of the usual shingle now in common use, though the construction is actually a number of shingle strips interlocked and then secured to the roof. The strip 1 is formed from a very thin sheet of copper 6 which is secured to a reinforcing sheet 7 by adhesive. The sheet 7 may be any desired flexible material but is preferably a desired grade of paper which has been impregnated with tar, asphalt, or other desired material. Usually the reinforcing sheet 7 is several times as thick as the copper, though this is not essential. The strips 1 may be made of any desired length and before they are applied to the roof they are formed into individual shingles 8 by being folded over to present the grooves 9 as shown in Fig. 2.

From Fig. 4 it will be observed that the strip 1 is folded over upon itself at 10 and then at 11 so as to present a bottom structure 12 in groove 9. The part 12 is folded over at 13 and then again at 14 so that the groove 9 will be provided and so that the copper covering will always be uppermost. A sheet of a desired length made up of shingles 8 is then in condition to be applied to a roof. In order to apply a number of strips to a roof it is necessary to interlock the successive strips as shown particularly in Figs. 1, 7, 8 and 10. As the parts have been folded over upon themselves more or less as illustrated in Fig. 4, the respective edges of the strips can not be folded at right angles if all of the reinforcing sheet 7 is left in place. In order to prevent kinking, buckling or breaking of the copper sheeting 6, the reinforcing strip 7 is formed with a substantially T-shaped cutaway portion 15 at each edge as illustrated particularly in Fig. 2. In view of this cutaway part there is nothing but

copper at this portion, and consequently the respective edges may be turned over as illustrated particularly in Figs. 8 and 10.

When two strips 1 are to be secured together they are arranged as shown in Fig. 7 with the copper sheeting in contact. A U-shaped metal clamp 16 is slid over the edges of the superimposed strips and then pressed so that the side walls thereof will tightly pinch the respective edges of the respective sheets. This reinforcing and clamping strip 16 is then turned over as shown in Fig. 8, after which the top sheet is swung over to the position shown in Fig. 10. Before the top sheet is swung over to the position shown in Fig. 10 a comparatively stiff metal plate 5 having a depending flange 17 is placed in position as shown in Fig. 10, and then one or more nails 4 applied. The plates 5 may be any desired length as, for instance, one plate may be the full length of the roof or several plates may be arranged end to end under a given strip 1. This provides a desired support for holding the respective sheets at an angle to the roof 3 and also provides means for securing the roofing to the wooden roof 3. After the second strip 1 has been applied as just described, the third strip may be applied to the second and so on for the full width of the roof 3.

When the successive strips are applied until the crown or apex 18 of the roof is reached or almost reached, a slightly different construction is utilized to provide a waterproof crown for the roofing. This is shown in detail in Fig. 12. As illustrated in this figure there is provided a retaining plate 19 of sheet metal which is comparatively stiff though capable of being bent. One of these is secured by nails 20 to each part of the roof 3, namely one on each side of the crown as shown in Fig. 12. The topmost strip 1 is arranged to have its edge portion lie against the larger section 19' of the retaining plate 19 as shown at the left in Fig. 12. The same arrangement is provided at the right. A strip 1 is then applied directly over the crown 1 and arranged so that its respective edges 21 will fold over the respective sections 19' of the respective plates 19. Then all the parts are pressed downwardly and eventually hammered until they assume the position shown at the right in Fig. 12. This completes the job of putting the crown piece in place.

In Figs. 13 and 14 a particular arrangement for the eaves is shown. A plate 22 is provided and is secured in place by nails or other means 23. This plate is similar to plate 19 and is provided with an enlarged section 22' over which the lowermost strip 1 is folded as illustrated in Fig. 13. The section 22' and the folded-over part of the strip 1 are then bent down and hammered into the position shown in Fig. 14, whereupon this part of the job is completed.

Where a valley is to be covered as shown in Fig. 15, the same particular arrangement as shown in Fig. 12 is used, except that the parts are reversed. The same strip 19 is used and the same general arrangement is provided, except that the valley strip 24 is caused to fit snugly the valley with the edge portions bent back upon the strip as indicated by the numeral 25. The lowermost strip 1 is then positioned with its edge portion 26 bent over the larger section 19' of the retaining plate 19 and also over the portion 25, after which all the parts are forced downwardly as indicated at the right in Fig. 15. This completes this part of the roof and presents a water tight connection between the various parts with-

out interfering with the various grooves 9 and the general arrangement of the roofing. If desired the strips 1 extending across the crown 18 and the strip 24 could be formed without the grooves 9.

It will be noted that the invention adapts itself to take care of various conditions of a roof, namely the roof body, the eaves, the crown and the valley. In all of these places a water tight structure is presented and the usual shingle appearance is maintained.

I claim:

1. A shingle strip comprising a sheet of copper and a reinforcing sheet secured thereto, said strip being formed with spaced transversely folded portions presenting on the face of the strip a plurality of spaced depressions for dividing the strip into shingle members, said reinforcing sheet being formed with cutout portions at the respective ends of said depression whereby the edge portions including a part of said folded-over portions of said strip may be folded without injuring the copper sheeting.

2. A rectangular shingle strip of the same width throughout comprising a comparatively narrow thin sheet of copper having straight parallel side edges, an impregnated reinforcing paper sheet of the same width and length as said copper sheet, and adhesive for rigidly securing the copper sheet to the paper sheet, said strip at spaced intervals being folded upon itself transversely for its full width to present division lines extending from one side edge to the other of the strip for dividing the strip into shingle member sections with each section of a length equal to the width of the strip.

3. A shingle strip comprising an asphalt impregnated sheet of paper having spaced substantially T-shaped cutouts adjacent each edge, a sheet of copper of the same width and length as said paper sheet, adhesive for securing said sheets together, said strip being folded transversely to present dividing lines, said folded portions extending across said T-shaped cutout portions of said paper sheet.

4. A roofing structure comprising a plurality of shingle strips, the respective edges of said strips at their point of overlapping being bent back so that the edges will interlock, a stiff retaining plate having a depending flange fitting over each of the interlocked portions, and a plurality of nails extending through the respective plates for securing the same to a roof and causing said depending flange to press said interlocked portions together and against said roof.

5. A roofing structure including a plurality of shingle strips, said strips overlapping except at the lower edge of the roofing structure, each of the overlapping edges being bent back from itself, a U-shaped clamping plate positioned to clamp the bent back portions and a retaining plate formed with a depending flange, said plate being positioned so that the depending flange will fit along the closed edge of said U-shaped structure, and securing members extending through said plate but not through the shingle strips.

6. The method of forming a joint between two shingle strips comprising the positioning of one shingle strip on the other in an inverted position, applying a U-shaped clamping member over the edge of the combined strips, then swinging the U-shaped structure and that portion of said shingle strips straddled by said U-shaped structure until they are above and parallel with the

- remaining part of the respective strips, and then bending the superposed strip over the U-shaped strip until it is in a substantially parallel plane with the U-shaped structure.
- 5 7. A shingle strip comprising a sheet of copper and a reinforcing sheet secured thereto, said strip being formed with spaced transversely folded portions presenting on the face of the strip a plurality of spaced depressions for dividing the strip into shingle members and to present means to control expansion and contraction of the strip caused by heat and cold, said reinforcing sheet being formed with cutout portions at the respective ends of said spaced depressions whereby 10 the edge portions of said strip may be folded transversely of said depressions without injuring the copper sheeting.
8. A shingle strip comprising an asphalt impregnated sheet of paper having spaced substantially T-shaped cutouts adjacent each edge, a sheet of copper of the same width and length as said paper sheet, adhesive for securing said sheets together, the strip formed by the paper and copper sheets being folded transversely to 15 present dividing lines, said folded portions extending across said T-shaped cutout portions of said paper sheet and presenting hot and cold expansion structures.
9. In a roofing structure, a plurality of shingle strips, one of said shingle strips being positioned to straddle the crown of a roof and extend a substantial equal distance on each side thereof, other roofing strips arranged on the roof below the crown on each side thereof, a substantially L-shaped plate on each side of said crown, means for securing said plates to the roof, the second mentioned shingle strips overlapping part 20 of said plates while the first mentioned strip overlaps the remaining part of both of said plates, said plates being bent downwardly until they are substantially parallel to the roof whereby the respective shingle strips are interlocked.
10. A roofing structure including means for mounting part of the structure at the eaves, said last mentioned means including a flexible strip of shingling material, a metal plate, means for securing the metal plate to the roof, said metal plate being formed to extend to the edge of the roof and then vertically downwardly, and said strip of shingling material being looped over the edge of said plate and clamped to the edge of the roof thereby.
11. A roofing construction comprising a plurality of strips of material interlocked along adjacent edges, each of said strips having spaced folded portions presenting a plurality of transversely extending depressions for dividing the strip into shingled members and to present means to control expansion and contraction of the strip caused by change of temperature, each of said strips being formed of a continuous sheet of copper and a reinforcing sheet of impregnated paper 10 of the same width and length as the copper sheet, said reinforcing sheet being formed with a cutout portion adjacent the respective ends of each of said folded-over portions, the interlocking part of adjacent strips having their edges bent 15 over so as to extend substantially parallel to the body of the strips, said cutout portions of said reinforcing sheet permitting the turning over of said edges without breaking said copper sheet adjacent said depressions, means for securing said turned-over portions together, a stiff retaining plate formed with a body extending from said interlocked edge and a depending flange positioned to fit along one edge of said securing means, and means extending through the body of said retaining plate for securing said plate and said interlocked portion to a roof.
12. A simulated shingle construction for use as a roofing or siding for a building comprising a plurality of strips each formed of a relatively thin sheet of metal secured to a sheet of flexible reinforcing material, each strip being formed at spaced intervals with pairs of proximately positioned parallel folds extending transversely of the strip and presenting means providing for expansion and contraction and for dividing the strip into simulated shingles, said strips being arranged in parallel relationship with the edges of adjacent strips overlapping and interlocked with each other, and attaching means for securing the strips to the roof or sides of a building.
13. A simulated shingle construction as set forth in claim 12 in which the attaching means includes retaining plates each comprising a body portion extending from the interlocked edges of adjacent strips beneath the strips, and a depending flange engaging the adjacent strips near the interlocked edges thereof, the flange serving to clamp the strips in position and to provide a butt portion for the simulated shingles.

HARRY F. WILDMAN.
